[57] CLAIM

The ornamental design for a reference table, as shown and described.

DESCRIPTION

FIG. 1 is a perspective view of a reference table showing my new design; the opposite side being a mirror image thereof;

FIG. 2 is a top plan view thereof;

FIG. 3 is a front elevational view thereof;

FIG. 4 is a rear elevational view thereof;

FIG. 5 is a perspective view of a modified form of the reference table shown in FIG. 1;

FIG. 6 is a top plan view thereof;

FIG. 7 is a front elevational view, the rear being identical thereto; and,

FIG. 8 is a side elevational view, the opposite side being a mirror image thereof.

FIG. 1

FIG. 2

FIG. 3
